UNITED STATES PATENT OFFICE.

ANDREW OEHMANN, OF WASHINGTON, DISTRICT OF COLUMBIA.

DESIGN FOR A GAME-BOARD.

58,937.

Specification for Design.

Patented Sept. 6, 1921.

Application filed October 25, 1920. Serial No. 419,545. Term of patent 7 years.

To all whom it may concern:

Be it known that I, ANDREW OEHMANN, a citizen of the United States, residing at Washington, in the District of Columbia, have invented a new, original, and ornamental Design for Game-Boards, of which the following is a specification, reference being had to the accompanying drawing, forming a part thereof.

The figure is a plan view of a game board, showing my new design.

I claim:

The ornamental design for a game board, as shown.

ANDREW OEHMANN.
